UNITED STATES PATENT OFFICE.

EDWARD VILLENEUVE, OF SALEM, MASSACHUSETTS.

UPPER-GUARD FOR HEEL-TRIMMING MACHINES.

SPECIFICATION forming part of Letters Patent No. 728,786, dated May 19, 1903.

Application filed January 17, 1903. Serial No. 139,420. (No model.)

To all whom it may concern:

Be it known that I, EDWARD VILLENEUVE, a citizen of the United States, and a resident of Salem, in the county of Essex and State of Massachusetts, have invented certain new and useful Improvements in Upper-Guards for Heel-Trimming Machines, of which the following is a specification.

This invention relates to improvements in an upper-guard for heel-trimming machines, and it is especially well adapted for use on that class of such machines termed "spring-heel trimmers;" and it has for its object means for preventing the rotary cutter from cutting too deep in the curved contour of the heel, for which purpose I employ, in combination with the rotary cutter and its shield, an adjustable upper-guard against which the upper is guided during the trimming operation, as will hereinafter be more fully shown and described, reference being had to the accompanying drawings, wherein—

Figure 1 is a top plan view of the invention, parts being shown in section. Fig. 2 is a longitudinal section on the line 2-2 shown in Fig. 1, and Fig. 3 is a bottom plan view of the improved guard.

Similar letters refer to similar parts wherever they occur on the different parts of the drawings.

In the drawings, A represents a portion of the head of a spring-heel trimmer of any well-known construction, and B represents a stationary part of the frame, as usual.

C is the heel-rest, against which the top lift of the heel to be trimmed is held during the trimming operation, as usual.

D represents a portion of the rotary trimmer-shaft, which is capable of longitudinal movement according to the height of the heel that is being trimmed.

E is the rotary cutter, secured to the shaft D, and F is the shield, secured to the outer end of the cutter, as usual.

G is the improved guard, having at its rear end a slot g, in which is longitudinally adjustable a block H, preferably provided with a slotted aperture h, adapted to receive the correspondingly-shaped end i of the bolt or post I, which latter is secured to the frame portion B or other suitable part of the machine. The outer end of the bolt portion i

is screw-threaded and provided with fastening-nuts K K', by means of which the block H may be firmly secured to the bolt I. 55

L is an adjusting-screw screwed through the outer end of the guard G and having its inner end universally connected to the block H, as shown in Figs. 1 and 2, so as to permit the guard G to oscillate in a horizontal direction relative to the block H during the longitudinal movement of the cutter E and its shield F. In practice the adjusting-screw L is connected by means of a ball-and-socket joint to the block H; but it may be otherwise 65 connected by similar mechanism without departing from the essence of my invention.

M is a spring interposed between the guard G and the frame portion B, and it serves for the purpose of holding the free end of the 70 guard in contact with the shield F during the longitudinal motion of the latter, as shown.

In dotted lines in Fig. 1, N represents the heel of the boot or shoe to be trimmed, O is the rand, and P represents the upper, as 75 usual. P, in dotted lines in Fig. 2, also represents a portion of the boot or shoe upper.

In one piece with or pivotally connected to the inner end of the guard G is an upper guide or nose G', which in practice I prefer 80 to pivot at g' to the inner end of the guard G, and said upper-guide is normally held in the position shown in the drawings by the influence of a suitable spring g¹¹, secured to the guard G and adapted to bear against the 85 guide G', as shown in Fig. 2.

During the operation of trimming the heel of the boot or shoe the top lift of the heel is held against the stationary heel-rest C, as usual. The contour of the heel to be trimmed 90 is held and adjusted by the operator with proper pressure against the rotary cutter and the shield F inserted in the rand at the junction of the heel and upper, as is usual in the art of trimming heels. During such 95 operation the upper portion of the boot or shoe is caused to bear against the upper-guide G', thus preventing the rotary cutter from cutting too deep on the curvature of the heel and causing the contour of the heel to be cut 100 parallel with and concentric relative to the contour of the upper. By having the nose G' yieldingly connected to the guard G it is capable of yielding upward when passing by

a backstay or seam at the rear of the upper, thus causing the heel to be trimmed evenly, and thus producing a perfect and uniformly-trimmed heel. By adjusting the position of the screw L the guard may readily be adjusted relative to the size of the cutter and its shield.

What I wish to secure by Letters Patent and claim is—

10. 1. In an upper-guard for heel-trimming machines, the combination with a stationary support, a cutter, and a cutter-shield, of a bar longitudinally adjustable upon and pivotally connected to said support, and provided at its free end with a yielding guard-nose, and a spring arranged to hold the side of the free end of said bar in contact with the cutter-shield, substantially as described.
20. 2. An upper guard for heel-trimming machines, the combination with a stationary support, a cutter, and a cutter-shield, of a bar longitudinally adjustable upon and pivotally connected to said support, a yielding guard-nose pivotally connected to the free end of said bar, a spring arranged to yieldingly hold said guard-nose against a shoe in contact with the cutter-shield, substantially as described.
30. 3. In an upper-guard for heel-trimming machines, the combination with a stationary support, a cutter, and a cutter-shield, of an oscillatory bar adjustably mounted upon said support, a yielding guard-nose pivotally connected to the free end of said bar, and a spring arranged to hold the side of the free end of

said bar in contact with the cutter-shield, 35 substantially as described.

4. In an upper-guard for heel-trimming machines, the combination with a stationary post, a cutter, and a cutter-shield, of a bar longitudinally slotted at one end, a block adjustably fitted in said slot and pivotally mounted on said post, means for adjusting said block in said slot, a yielding guard-nose pivotally connected to the free end of said bar, and a spring arranged to hold the free end of said 45 bar in contact with the cutter-shield, substantially as described.

5. In an upper-guard for heel-trimming machines, the combination with a stationary post, a cutter, and a cutter-shield, of a bar longitudinally slotted at one end, a block adjustably fitted in said slot, an adjusting-screw mounted in said end of the bar and swiveled at its end in said block, the said block being pivotally mounted on said post, a yielding 50 guard-nose pivotally connected to the free end of the bar, a spring arranged to hold said guard-nose against the shoe-upper, and a spring arranged to hold the side of the free end of the said bar in contact with the cutter-shield, substantially as described.

In testimony whereof I have affixed my signature in presence of two witnesses.

EDWARD VILLENEUVE.
